UNITED STATES PATENT OFFICE.

CHARLES KELSH, OF PHILADELPHIA, PENNSYLVANIA, ASSIGNOR TO AUGUSTUS A. LAZARUS, ISAAC A. SCHIWARZ, AND BENJAMIN LIPPER, ALL OF SAME PLACE.

DESIGN FOR TRIMMING.

SPECIFICATION forming part of Design No. 19,581, dated January 14, 1890.

Application filed December 19, 1889. Serial No. 334,323. Term of patent 3½ years.

To all whom it may concern:

Be it known that I, CHARLES KELSH, a citizen of the United States, and a resident of Philadelphia, Pennsylvania, have invented a 5 Design for Trimming, of which the following is a specification.

My design is fully shown in the accompanying drawing, and consists of an open-work or reticulated band *a*, forming a background 10 for surface ornamentation, comprising cords *b* and *d*, which follow a serpentine course, so as to form successive tapering figures extending across the band. At one edge of the band is a border comprising scallops *f* and 15 tongues or fingers *g g'*, projecting therefrom into the body of the trimming, the fingers *g'* being longer than the fingers *g*, so as to partially fill the spaces between the narrow or

pointed ends of the tapering figures formed by the cords *b d*. This border forms one of 20 the essential features of the design.

I claim—

The within-described design for trimming, said design consisting of the reticulated background with its surface ornamentation of tapering figures, and the border composed of scallops and inwardly-projecting fingers, substantially as described and shown. 25

In testimony whereof I have signed my name to this specification in the presence of 30 two subscribing witnesses.

CHARLES KELSH.
